UNITED STATES PATENT OFFICE.

WILLIAM G. SANDERSON, OF CHICAGO, ILLINOIS.

FIRE-EXTINGUISHER.

1,299,235.

Specification of Letters Patent.

Patented Apr. 1, 1919.

Application filed May 15, 1916. Serial No. 97,473.

To all whom it may concern:

Be it known that I, WILLIAM G. SANDERSON, a citizen of the United States, residing at Chicago, in the county of Cook and State 5 of Illinois, have invented certain new and useful Improvements in Fire-Extinguishers, of which the following is a specification.

My invention relates to improvements in fire extinguishers, and more particularly 10 to one of the hand operated type, in which a suitable fire extinguishing fluid, such for example as carbon tetrachlorid, is expelled from the container in a jet or spray by means of a hand impelled piston. 15 It is common practice in extinguishers of this type to provide an axially fixed but rotatable screw extending through the center of the container and piston, the piston being threaded for engagement with the screw so 20 that on the rotation of the latter the piston is forced inwardly to expel the fluid. One of the faults inherent in such extinguishers is the difficulty of preventing leakage of the volatile fluid through the piston along the 25 screw threads. As lubrication is well nigh impossible the threads on both the piston and screw must necessarily be cut to permit free and easy relative movement, as a screw fitting sufficiently tight to stop the leakage 30 would increase the frictional resistance to the operation of the extinguisher to a prohibitive degree. To secure the end of the screw to the rear face of the piston would necessitate extending the screw stem through 35 the rear head of the container, obviously doubling the overall length of the apparatus. Aside from the clumsy appearance of such a structure the long threaded rod would be exposed to injury such as bending, or mutilation of the threads, either of 40 which would render the extinguisher inoperative.

One of the objects of my invention is to provide an efficient and reliable hand extinguisher in which an imperforate piston 45 may be used, and to accomplish this I have provided what is termed a telescoping screw in which a plurality of concentric tubular screw members inter-engage, one with the 50 other, so that the overall length of the screw when extended is approximately the collapsed length multiplied by the number of screw members used. By using such an arrangement any suitable imperforate piston

may be used, as it is secured directly to the 55 screw, there being no relative movement of the two parts.

Obviously the use of such a piston feeding mechanism increases but little the overall 60 length of the extinguisher casing and as the screw does not pass through the fluid containing chamber it may be suitably lubricated to facilitate its operation.

The principal object, therefore, of my invention is to provide a hand extinguisher 65 in which a screw feed is used in combination with an imperforate piston, the overall length of the extinguisher being but little greater than that of the type now in use.

Another object of my invention is to provide such an extinguisher in which an oval, or non-cylindrical casing is used to prevent 70 rotation of the piston with respect to its impelling screw mechanism.

A further object of my invention is to provide an extinguisher in which the extinguishing fluid comes in contact only with the 75 walls of its container, thereby protecting the operating mechanism from chemical action.

Still other and further objects of my invention will become apparent to those skilled 80 in the art from a consideration of the following description and drawings wherein—

Figure 1 is a diametrical sectional view through my improved extinguisher. 85

Fig. 2 is a transverse sectional view on the line 2—2 of Fig. 1.

Fig. 3 is a fragmentary sectional view on the line 3—3 of Fig. 1, and

Fig. 4 is a diametrical sectional view 90 through a modification.

The apparatus comprises in general a fluid chamber 10 within which is reciprocally mounted imperforate piston 11, which is forwardly impelled by means of the telescoping screw members indicated in general by the numeral 12, these in turn being driven by the handle 13. The apparatus is constructed of such a size as to be readily carried from place to place and discharged 100 by the operator. In operation the user grasps the body of the chamber 10 with one hand, directs the nozzle 14 at the base of the fire, and turns the handle 13 with the other hand, thus impelling the piston forward and 105 ejecting a stream of fluid.

More specifically the structure comprises a metal tube 15 of oval cross section pro-

vided with a concaved head 16 which seamed into its forward end, as at 17. A nozzle valve of any suitable type may be used, that illustrated comprising a nipple 18, internally threaded as at 19 to receive the threaded projection 20 of the winged nozzle 21. The nipple 18 is provided with an eccentric bore 22, whereas the bore 23 in the nozzle is concentric. Because of this arrangement of non-alining bores it is obvious that when the winged nozzle is screwed to the innermost end of its travel, both bores are closed whereas a passage way is opened when the nozzle is rotated in the opposite direction.

A flanged head 24 closes the upper end of the tubular member 15 and is provided with a cylindrical extension casing 25 within which is mounted the telescoping feed screw. The feed screw comprises four parts, a central threaded spindle 26 on the outer end of which is mounted the handle 13, and three concentric tubular screw members 27, 28 and 29. The upper end of the tubular member 27 is provided with an inwardly extending annular shoulder 30 which is internally threaded for engagement with the threaded rod 26, its outer surface being screw threaded for engagement with a similar internally threaded shoulder 31, carried on the upper end of the tube 28. The outer surface of the tube 28 is similarly threaded for engagement with an internally threaded head 32, on the outer tube 29. A cap 33 is detachably secured on the lower end of the threaded rod 26 to prevent the threaded shoulder 30 from running over the end of the rod when it is turned down, and for the same reason I have provided outwardly projecting annular shoulders 34 and 35 on the lower ends of the tubes 27 and 28, respectively, for engagement with the shoulders 31, 32.

The piston which I have illustrated as comprising an oval plate 36 carrying a packing disk 37 of suitable material on its inner face is secured to the inner or lower end of the tube 29. As a suitable means of securing the tube to the piston I have provided an outwardly formed annular bead or groove 38, perforated to receive a series of prongs 39 formed from the lower end of the tube 29, the ends of the prongs being turned over as at 40 to rivet the two parts together.

To prevent axial displacement of the central threaded rod 26 I have provided an annular shoulder 41 near the upper end thereof for engagement by the cap nut 42 which is in screw threaded engagement with the upper end of the casing tube 25. A packing collar 43 overlies the upper end of the tube 25 and engages the under side of the annular shoulder 41.

From the description it will be evident that rotation of the handle 13 causes the extension of the telescoping screw sections

pressing the piston 36 downward in the cylinder and ejecting the fluid. As there are four extensible screw members provided in the embodiment illustrated in Fig. 1, it will be obvious that the length of the casing 25 70 projecting from the head of the extinguisher need be but approximately a third the length of the extinguisher casing within which the piston travels. The screw may have either right or left hand threads depending upon 75 the direction in which the handle is to be rotated. In the illustrated embodiment the threads are cut for left hand, or counter clockwise, rotation.

In Fig. 4 of the drawings I have illustrated a modification which the invention might take and in which the movement of the piston is secured by the turning of a hand crank 50 projecting from one side of the casing and carrying on its inner end a beveled pinion 51 engaging with a beveled gear 52, secured to the lower end of the outer tubular extensible screw member 53. In this instance the parts are reversed, that is, the outer tubular member is the rotated 90 driving part whereas the inner screw threaded spindle 54 is connected at its lower end with the piston 36'. In this embodiment I have shown but three extensible members, 95 namely the inner threaded spindle 54, a concentric tube 53, having at its lower end an internally threaded shoulder 56 which engages with the threaded spindle 54, and an outer axially fixed but rotatable shell member 53, the lower end of which is provided with a shoulder and internally threaded, as at 57, for engagement with the external threads on tube 55. The upper end of the shell 53 is provided with an outwardly extending annular flange 58 which is held 100 from axial movement by the cap nut 59, screw threaded on the upper end of the inclosing casing tube 60.

The operation of the modification illustrated in Fig. 4 is the same as that shown in 110 Fig. 1 except that the screw movement is accomplished by a different driving mechanism.

Whereas I have illustrated and described but two embodiments of my invention it is 115 obvious that various other modifications and changes may be made without departing from the spirit and scope of the appended claims.

Having described my invention, what I 120 claim is:

1. In a hand operated fire extinguisher, the combination of a fluid containing tube, an imperforate piston reciprocable therein, a closure head for one end of the tube, a 125 plurality of telescoping inter-engaging screw members, one of said members being secured to the piston, a casing carried by the said head and inclosing the screw members when in telescoped position, and means 130

projecting through said casing for rotating one of the screw members not connected with the piston.

2. In a hand operated fire extinguisher, 5 the combination of a fluid containing tube, an imperforate piston reciprocable therein, means for preventing rotation of the piston with respect to the tube, a threaded rod concentric with the tube and rotatable with respect thereto, means for preventing axial 10 movement of the rod, a plurality of interengaging tubes telescoping one within the other, the inner being in threaded engagement with the rod, and means for securing 15 the outer of said tubes to the piston.

3. In a hand operated fire extinguisher the combination of a fluid containing tube, 20 an imperforate piston reciprocable therein, means for preventing rotation of the piston with respect to the tube, a head for one end

of the tube, an axially disposed cylindrical casing projecting outwardly from the head, a threaded rod positioned axially within the casing, a plurality of internally and externally threaded tubes adapted to telescope 25 within each other, the inner tube being in threaded engagement with the said rod and all of the tubes, when in telescoped position lying within the casing, means connecting the outer of the tubes with the piston, and 30 means carried by the outer end of the casing for preventing axial movement of the threaded rod.

In testimony whereof I hereunto set my hand in the presence of two subscribing wit- 35 nesses.

WILLIAM G. SANDERSON.
